SEPARATION OF VOLATILE CONSTITUENTS
FROM CRUDE SOAPS

1931

7 Claims. (Cl. 202—53)

The present invention relates to the separation of volatile constituents from crude soaps.

We have found that aqueous crude alkali metal soaps prepared from materials containing fatty acids of high molecular weight, e. g. those having at least 10 carbon atoms, or mixtures thereof, such as products of the oxidation of aliphatic hydrocarbons of high molecular weight and of mixtures thereof, or fats, oils or waxes of natural origin can be freed from volatile substances of high boiling point contained therein in a manner which is simple industrially by heating the aqueous crude soaps to the melting temperature of the anhydrous soaps in a closed vessel so that an initial increased pressure is generated and the mass remains continually liquid, releasing the pressure and then removing the volatile constituents from the anhydrous melt at the same or a more elevated temperature by distillation, if desired while employing a vacuum or while passing through steam or other inert gaseous agent such as nitrogen, carbon dioxide or inert industrial waste gases. In this manner, by reason of the fact that the mass is continually kept in the liquid state notwithstanding the removal of water, it may be readily brought without inconvenience to the temperatures necessary for the removal of the volatile substances of high boiling point, such as alcohols, aldehydes, ketones or hydrocarbons, or mixtures thereof having a boiling point above 100° C., and the distillation of the said substances proceeds rapidly and without injurious decompositions. The minimum pressure necessary to produce this effect during the heating up to the melting temperature depends on the nature of the saponification products to be worked up; in most cases pressures of from about 10 to about 30 atmospheres are sufficient, but higher pressures may be employed. The melting temperatures, which lie generally between about 200° and about 300° C. and usually between 250° and 300° C., are also dependent on the nature of the initial materials; they may be readily ascertained by preliminary experiments.

The initial materials for the process according to the present invention may be chosen from all crude products of the saponification of fatty acid materials containing non-saponifiable constituents of high boiling point, as for example natural waxes, such as mineral waxes containing esters such as crude Montan wax, physically or chemi-

cally bleached Montan wax, or vegetal, i. e. animal or vegetable waxes, such as wool grease, sperm oil, spermaceti and the like, oxidation products of liquid or solid non-aromatic hydrocarbons, such as paraffin wax, paraffin oil or high-boiling mineral oil fractions, which oxidation products contain high molecular fatty acids, alcohols, aldehydes and ketones, products of the catalytic hydrogenation of vegetal fatty acids or esters which products often contain some fatty acids and some hydrocarbons besides alcohols and may consist of esters of the said fatty acids with the corresponding saturated alcohols. The quantity of water in the said crude soaps is generally so high that a mass is obtained in the saponification which can be easily stirred by mechanical means as are usual in the soap industries. The quantity of alkali present in the crude soaps may be equivalent to those of fatty acid present but it may be higher or lower, the saponification requiring often an excess of alkali and, on the other hand, may be often carried out with a lower quantity of alkali depending on the resistance to saponification of the initial materials and on the nature of the alkali employed.

The process may be carried out for example by first heating the aqueous saponification product in a closed vessel, preferably while stirring or otherwise causing movement, until the necessary minimum pressure ascertained by a preliminary test with a small quantity in a small vessel has been produced then while maintaining the said pressure, which may be effected by periodically releasing the pressure, heating the mass to the melting temperature of the anhydrous saponification products and removing the water contained in the saponification products in the form of water vapor by releasing the pressure. The volatile constituents then distil off at the same or a more elevated temperature because the fused saponified mass in contrast to an intermediately dried product is capable both of absorption of heat and degasification. The distillation may be accelerated by leading in steam or inert gases, by the employment of a vacuum and/or by stirring or otherwise moving the saponified mass, as for example with the aid of rotating vessels or by allowing it to flow along the walls of a vessel. The heating of the saponification products to the melting temperature, the releasing of the pres-

sure and the distillation of the volatile constituents may be carried out in batches in a pressure-tight stirring vessel capable of being heated and provided with the necessary supply and withdrawal pipes for supplying and withdrawing the saponification products and for distilling off the vapors and if desired also for blowing in steam or gases. It is of especial advantage, however, to carry out the process in a continuous manner and only to expose the product for a very short time to the high and, during a too protracted action, injurious temperatures. For example the saponification product may be heated in a closed stirring vessel as hereinbefore described only to such an extent that the necessary minimum pressure is attained. While making use of the pressure, the mass is then led from the stirring vessel through a tube system heated to the said or higher temperatures at the end of which the fused mass is released from pressure and at the same time freed from water vapor in a chamber which is likewise heated to the said temperatures and in which the mass is subjected to distillation for the removal of impurities. The heating of the apparatus is preferably carried out while avoiding injurious overheating, as for example by means of metal baths the temperature of which is not allowed to exceed the predetermined limits. The melt of soaps freed from volatile constituents may be rapidly removed from the hot distillation zone by its own weight or by employing conveyor devices and may then be cooled. In this manner soaps which are quite anhydrous and substantially free from volatile substances of high boiling point may be obtained. If, however, it is desired to recover the saponification product directly in the form of an aqueous solution it is preferable, after separating the volatile constituents, to bring the soap melt into contact in a closed system with such an amount of water or water vapor that the minimum pressure prevailing during the heating is produced again and is maintained by the supply of water or water vapor until the whole has cooled to about the temperature at which previously the said pressure had been produced by heating. In this manner a ready cooling and dissolution of the saponification products is rendered possible without inconvenience.

50 The process according to the present invention is especially suitable for separating unsaponifiable constituents of high boiling point from saponification products of substances containing fatty acids, especially of oxidation products of aliphatic hydrocarbons of high molecular weight. It may also be employed, however, for the removal of constituents of low boiling point from the said saponification products; for example it allows of the direct preparation of completely anhydrous saponification products from solutions thereof. Furthermore, treatments of the saponification products other than distillation which necessitate a heating of the saponification products to from about 200° to 300° C. may be carried out according to the present invention or may be combined therewith. For example the process may be used with special advantage in the working up of oxidation products of hydrocarbons obtainable for example by the treatment of paraffin wax, paraffin oil, high-boiling mineral oil fractions or the like with nitric acid or oxides of nitrogen. If products of the said kind are heated in alkaline solution to from 200° to 250° C. under pressure for the purpose of splitting off nitrogen, they may be immediately afterwards freed from

volatile unsaponifiable substances according to the present invention and thus alkali metal salts of the fatty acids freed from volatile constituents are obtained in one operation and the pure carboxylic acids may be readily obtained in any known and convenient manner from the said salts.

The following examples will further illustrate the nature of this invention but the invention is not restricted to these examples. The parts are by weight.

Example 1

1500 parts of an oxidation product (obtained by the treatment of 1350 parts of hard paraffin wax with a 60 per cent nitric acid at 80° C. for about 8 hours) having an acid value of 128, a saponification value of 243, a content of 17.5 per cent of unsaponifiable material and 3.17 per cent of nitrogen are mixed with 1800 parts of a 20 per cent aqueous caustic soda solution and heated to 230° C. in an autoclave while stirring. A pressure of 25 atmospheres is thus produced. The soap solution is led under pressure through a spiral tube which is situated in a lead bath heated to 340° C. and is introduced, with the simultaneous release of pressure, into a vessel provided with a stirring device, a temperature of 320° C. being maintained in the said vessel. The fused saponification product leaves the vessel through a siphon arranged in the lower part thereof, while the vapors of the unsaponifiable substances together with the steam escape through an outlet pipe and are condensed. In this way 300 parts of unsaponifiable substances are obtained. The pure saponification product is dissolved in water and decomposed by means of hydrochloric acid. The fatty acids which separate have the following characteristics: acid value 265, saponification value 271, content of unsaponifiable substances 3.1 per cent, nitrogen 0.49 per cent. During a distillation of these fatty acids, a part of the unsaponifiable substances remains behind in the distillation residue so that, calculated on the initial amount, 77 per cent of fatty acids containing only 1.6 per cent of unsaponifiable substances are finally obtained.

Example 2

5000 parts of crude paraffin wax are well stirred at 75° C. in an acid-proof and pressure-tight vessel for 12 hours with 8000 parts of a 50 per cent aqueous nitric acid; the pressure of oxides of nitrogen thus produced is regulated to 5 atmospheres and kept constant by periodically releasing the pressure. After separating off the nitric acid, 5600 parts of an oxidation product having a saponification value of 180, a nitrogen content of 2.4 per cent and a content of 25 per cent of unsaponifiable substances are obtained. The product is saponified by heating it to 100° C. in an open vessel until carbon dioxide is removed with 4000 parts of a 25 per cent aqueous sodium carbonate solution and then heated to from 200° to 220° C. in a pressure-tight iron container; a pressure of water vapor of from 20 to 24 atmospheres is thus set up. A small quantity of water vapor is allowed to escape from the reaction vessel until it no longer contains ammonia, that is until the nitrogen has been split off from the oxidation product. Then, while keeping the pressure constant at about 25 atmospheres, the temperature is increased to 260° C. and the remainder of the water vapor is allowed to escape. Superheated steam in a state of fine division is then blown at

atmospheric pressure, or advantageously in vacuo, through the now anhydrous liquid saponification product while stirring continually, the steam being condensed together with the distilled 5 unsaponifiable substances outside the stirring vessel. The temperature of the saponification product is then increased to 310° C. After about 1 hour, 1300 parts of unsaponifiable substances, mainly consisting of paraffin wax, have been 10 expelled from the saponification product. The mass is cooled by pressing in about 3000 parts of cold water, withdrawn from the stirring vessel and acidified with aqueous nitric acid. In this way an upper layer of 3900 parts of dark brown 15 fatty acids is obtained which may be further worked up into pure pale fatty acids by distillation with steam in vacuo at from 0.1 to 0.01 atmosphere. The fatty acids obtained in the manner contain only from 1 to 2 per cent of unsaponifiable 20 substances and 0.1 per cent of nitrogen.

Example 3

100 parts of wool fat having a saponification value of 88 are heated while stirring in an autoclave with 35 parts of a 20 per cent aqueous caustic soda solution and 75 parts of water. As soon as a pressure of 30 atmospheres is attained heating is continued while blowing off steam in such a quantity that the pressure remains constant. As soon 30 as the mass has attained a temperature of from 250° to 260° C. the pressure is completely released whereby the steam is wholly blown off. The soap in the autoclave is then heated to 350° C. while blowing through steam for facilitating the distillation of the volatile constituents. The vapors are passed through a condenser heated to from about 70° to about 80° C. so that volatile matter distilled off is condensed.

In this manner 42.5 parts of the unsaponifiable 40 matter contained in the wool fat are obtained. The soap remaining as the distillation residue is then split with the aid of acid in any usual and convenient manner whereby 48 parts of the acids of wool fat are obtained which show an acid 45 value of 128, a saponification value of 139 and a content of unsaponifiable matter of 14.5 per cent.

Example 4

1000 parts of sperm oil having a saponification value of 150 are heated in an autoclave while stirring to 200° C. together with 590 parts of a 20 per cent aqueous caustic soda solution and 530 parts of water, whereby a pressure of 18 atmospheres is attained. The whole is then kept for 3 hours at the said temperature for rendering complete the saponification, passed by the prevailing pressure into a pipe system in which it is heated to 300° C. while maintaining the pressure and then released through a second pipe system connected into a separator in which the temperature is kept at 300° C. The separator is provided at its bottom with a siphon from which the molten soap is drawn off while the vapors are drawn off through an outlet pipe connected to the top of the separator and then led to a condenser in which they are precipitated by indirect cooling with the aid of water warmed to from 70° to 80° C.

In this manner, after the separation of the 70 water, 350 parts of unsaponifiable material, that is almost the whole quantity of alcohols of high molecular weight contained in the original sperm oil, are obtained which alcohols show a saponification value of from 2 to 3 only and which therefore may find useful application without purification. From the molten soap the fatty acids

can be obtained in any usual and convenient manner of cleavage in a quantity of 615 parts which show a saponification value of 206, and acid value of 198 and a content of 2 per cent only of unsaponifiable constituents. The acids may 80 be employed for the production of soap either as such or after a distillation.

What we claim is:—

1. In the separation, by distillation, of volatile, unsaponifiable matter from crude soaps the step 85 which comprises heating an aqueous, crude soap containing volatile, unsaponifiable substances at a pressure between 10 and about 30 atmospheres to the melting point of the soap, when in the anhydrous state, releasing the pressure and then distilling off the said volatile, unsaponifiable substances at a temperature at least as high as the aforesaid temperature.

2. In the separation, by distillation, of volatile, unsaponifiable matter from crude soaps the step 90 which comprises heating an aqueous, crude soap containing volatile, unsaponifiable substances to from about 250° to about 300° C., at a pressure between 10 and about 30 atmospheres, releasing the pressure and then distilling off the said volatile, unsaponifiable substances at a temperature 100 at least as high as the aforesaid temperature.

3. In the separation, by distillation, of volatile, unsaponifiable matter from crude soaps the step 105 which comprises heating an aqueous, crude soap containing volatile, unsaponifiable substances to from about 250° to about 300° C. at a pressure between 10 and about 30 atmospheres, releasing the pressure and then distilling off the said volatile, unsaponifiable substances at a temperature 110 at least as high as the aforesaid temperature, while passing through a current of an inert gaseous agent.

4. In the separation, by distillation, of volatile, unsaponifiable matter from crude soaps, the step 115 which comprises heating an aqueous, crude alkali metal soap, from the products of an oxidation of difficultly volatile, non-aromatic hydrocarbons and containing volatile, unsaponifiable substances, at a pressure between 10 and about 30 120 atmospheres to the melting point of the soap when in the anhydrous state, releasing the pressure and then distilling off the said volatile, unsaponifiable substances at a temperature at least as high as the aforesaid temperature.

5. In the separation, by distillation, of volatile, unsaponifiable matter from crude soaps, the step 125 which comprises heating an aqueous, crude alkali metal soap, from the products of an oxidation of difficultly volatile, non-aromatic hydrocarbons 130 and containing volatile, unsaponifiable substances, at a pressure between 10 and about 30 atmospheres to the melting point of the soap when in the anhydrous state, releasing the pressure and then distilling off the said volatile, unsaponifiable substances with the aid of steam at 135 a temperature at least as high as the aforesaid temperature.

6. In the separation, by distillation, of volatile, unsaponifiable matter from crude soaps, the 140 step which comprises heating an aqueous, crude sodium soap from the saponification of products of an oxidation of paraffin and containing volatile, unsaponifiable substances, to from about 250° to about 300° C. at a pressure between 10 145 and about 30 atmospheres, releasing the pressure and then distilling off the said volatile, unsaponifiable substances at a temperature at least as high as the aforesaid temperature.

7. In the separation, by distillation, of volatile, 150

unsaponifiable matter from crude soaps, the step which comprises heating an aqueous, crude sodium soap from the saponification of sperm oil and containing alcohols of sperm oil esters to about 200° C. at a pressure of about 18 atmospheres, heating the whole to about 300° C., while

maintaining the said pressure, releasing the pressure and separating the vapors formed from the liquid soap.
